(57) **CLAIM**

The ornamental design for a liquid dispensing apparatus, as shown and described.

DESCRIPTION

FIG. 1 is a front perspective view of the embodiment of a liquid dispensing apparatus;

FIG. 2 is a rear perspective view of the liquid dispensing apparatus of FIG. 1;

FIG. 3 is a top view of the liquid dispensing apparatus of FIG. 1;

FIG. 4 is a side elevational view of the liquid dispensing apparatus of FIG. 1;

FIG. 5 is a side elevational view of the liquid dispensing apparatus of FIG. 1 taken from the side opposite that of FIG. 4;

FIG. 6 is a bottom view of the liquid dispensing apparatus of FIG. 1;

FIG. 7 is a front elevational view of the liquid dispensing apparatus of FIG. 1; and,

FIG. 8 is a rear elevational view of the liquid dispensing apparatus of FIG. 1.
